BOOT

George H. Bingham, Jr., Taneytown, Md., assignor to Cambridge Rubber Company, Cambridge, Mass., a corporation of Maryland

Application May 21, 1953, Serial No. 25,158

Term of patent 14 years

(Cl. D7—4)

To all whom it may concern:

Be it known that I, George H. Bingham, Jr., a citizen of the United States of America, residing at Taneytown, county of Carroll, and State of Maryland, have invented a new, original, and ornamental Design for a Boot, of which the following is a specification, reference being had to the accompanying drawing, forming a part thereof.

Figure 1 is a side perspective view of a boot embodying my new design;

Figure 2 is a similar view showing the opposite side of the boot;

Figure 3 is a view similar to Figure 1 with the boot open; and

Figure 4 is a rear elevational view of the boot, as shown in Figure 1.

I claim:

The ornamental design for a boot, as shown.
